CLAIM

The ornamental design for an electronic device, as shown and described.

DESCRIPTION

FIG. 1 is a front perspective view of an electronic device showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion of the electronic device taken from FIG. 2; and,

FIG. 10 is an enlarged view of a portion of the electronic device taken from FIG. 5.

The dot-dashed broken lines in the figures are for the purpose of illustrating from where the enlarged views are taken and form no part of the claimed design.

The shade lines in the figures show contour and not surface ornamentation.

The oblique shade lines in the figures show transparency or translucency.
